UNITED STATES PATENT OFFICE.

MATTS JOHNSON, OF SPOKANE, WASHINGTON, ASSIGNOR OF ONE-FOURTH TO NELS P. NELSON AND ONE-FOURTH TO OSCAR CARLSON, BOTH OF SPOKANE, WASHINGTON.

BAKING OVEN.

Application filed March 22, 1924. Serial No. 700,991.

The present invention relates to improvements in baking ovens, especially adapted for use in connection with knockdown or separable stoves or furnaces in which the several parts of the stove or furnace are adapted to be readily separated in order to insure packing into a small compass for facile transportation and shipment, and also to provide for easy manipulation in assembling the stove or furnace as well as in dismantling the structure.

In the present form of the invention as illustrated the oven is enclosed within a heating chamber receiving heat from a firepot beneath the oven in which coal is preferably used for fuel, although other forms of fuel may be utilized. Means are provided for adjusting or varying the size and capacity of the baking chamber of the oven, and means are also provided for directing the path of gases of combustion and heat currents around the oven in order that baking may take place therein with economy in fuel and in such manner as to insure proper and correct conditions for baking various articles as required.

The invention consists in certain novel features of construction and combinations and arrangements of parts as will be hereinafter more fully set forth.

In the accompanying drawings I have illustrated one complete example of the physical embodiment of my invention wherein the parts are combined and arranged in accordance with the best mode I have thus far devised for the practical application of the principles of my invention.

Figure 1 is a front view in elevation of a stove or furnace in which the oven of my invention is embodied for use.

Figure 2 is a detail view in side elevation showing a portion of the front of the stove or furnace with the oven door open and supported upon brackets.

Figure 3 is a detail view partly in section showing the operation and positions of interior, adjustable heat deflecting plates used in connection with the oven.

Figure 4 is an enlarged, vertical, transverse sectional view of the stove or furnace, illustrating the relative positions of the oven, firepot and other elements of the structure.

Figure 5 is a view in perspective of one of a duplicate pair of exterior clamping

frames for retaining the separable parts of the furnace structure.

Figure 6 is a longitudinal, vertical section view of the furnace and oven.

Figure 7 is a perspective view of the oven detached.

In carrying out my invention I preferably utilize a furnace structure of oblong shape with rectangular walls and of separable parts including the bottom plate 1 of metal, at the underside of which are detachably secured the four corner legs 2, for elevating the structure to a suitable height. The front plate 3 and rear plate 4, together with the two side walls 5 and top 6 complete the enclosing structure of the furnace.

The two side walls and the front and rear walls of the stove structure are each fashioned with upper and lower exterior, horizontally extending flanges 7 which project outwardly therefrom to the edges of the bottom and top plates respectively, and these two thicknesses of material are embraced by a pair of retaining frames of which the bottom one is designated 8 and the top one 9. As seen in Figure 5 each frame is of rectangular form and made up of four sections 10 of channel iron or U-shape in cross section and the sections have mitered ends as shown.

These frames embrace the outer edges of the top and bottom plates and their complementary flange members and bolts 11 are passed through perforations 12 of the frame and registering holes in the flanges and plates for retaining the frames in position and forming a rigid stove structure.

The fire pot extends longitudinally of the stove and its walls 13 of metal rest upon the bottom plate of the stove which is slotted within the area of the refractory lining 14 of the fire pot. The metallic plates 13 forming the side walls of the fire pot are flanged as at 18' and these flanges are screwed or bolted to the slotted bottom plate as seen in Figure 4. Within the firepot and upon a level with the bottom plate 1 is arranged an oscillating or oscillatory grate 15 of suitable structure, and below the grate a detachable ash-pan 16 is suspended. The pan at its upper longitudinal edges is fashioned with outwardly extending guide flanges 17, slideable in the trackways 18 attached at the underside of the bottom plate 1, and it will be apparent that the ashpan may with con-

venience be withdrawn from its connected position at the underside of the bottom plate for storing or shipping.

At the front of the ashpan a slide damper 5 16' is provided to control the draft to the fire supported on the grate 15.

At the exterior of the front plate 3 a well known type of oven door 19 is hinged at 19' to swing outwardly and downwardly, and

10 when in this outward position the door is supported in horizontal position on a pair of swinging bracket arms 20 pivoted at 20' near the respective ends of the oven door.

Fuel is supplied to the grate through the 15 opening in the front plate below the oven door, which is closed by the hinged door 21 that is provided with a draft slide or damper 22 of suitable type, and additional dampers 23 may be provided in the front plate adjacent to the lower corners of the fuel door.

20 Within the walls of the stove structure an ample heating chamber 24 is provided to receive heat from the burning fuel in the grate, and the oven is suspended in this 25 chamber above the grate and in position to receive heat from the upwardly moving gases of combustion and heat currents from the fire.

The oven is made up of two sections, the 30 lower one of which is fixed within the heating chamber and comprises a metal bottom plate 25 and side plates 26 extending upwardly therefrom, and a refractory lining of fire brick or other suitable material indicated at 27 is provided within this section. The section of the oven extends from front to rear of the heating chamber and at its ends is closed by these front and rear walls of the heating chamber. At the underside 35 40 of the bottom plate 25 of the oven depending end flanges 28 are fashioned, and bolts or screws 29 may be utilized to secure the flanged bottom plate of the oven to the front and rear walls of the heating chamber, as 45 best seen in Figures 4 and 6.

The top section of the oven is movable and adjustable with relation to the lower section of the oven for the purpose of varying the interior cubicle contents of the oven 50 to adapt it for various articles to be baked. This movable and adjustable top section comprises a top metallic plate 30 having side walls or flanges 31 depending therefrom and adapted to telescope within the side walls 26 55 of the lower section. Upright guide bars 30 may be provided within the lower section of the oven to guide the walls 31 of the upper section in their vertical movement and to close the ends of the oven against ingress of 60 gases of combustion.

The adjustable oven section is moved vertically with relation to the lower oven section through the instrumentality of a pair of screw bars 32 one of which is secured near 65 each end of the oven section, and the screw

bars are of course centrally alined on the top of this movable section. These screw bars project upwardly through bearing openings 33 in the top plate 6 of the stove, and hand wheels 34 threaded on these screw bars are utilized in well known manner to elevate or permit lowering of the oven top when the wheels are turned in proper manner on the screw bars.

70 Due to the updraft from the fire in the fire pot the heated currents of air and gases of combustion pass upwardly and come in direct contact with the bottom of the oven for heating the interior of the oven through the metal bottom and refractory lining 80 therein. The heated currents of air then pass laterally from under the oven and up the exterior surfaces of the sides of the oven, between the oven and the side walls of the stove as indicated in Figure 4 by passages 4' 85 at the respective sides of the oven.

To guide and direct these upwardly moving heated air currents I utilize a pair of deflector plates 35 and 36 and a pair of spaced angle iron plates 37 which form a flue 38 leading to the thimble 39 of the smoke pipe 40.

90 The two deflector plates are hinged at 41, the hinge pins extending longitudinally of the heating chamber and preferably carried by the side plates of the stove as seen in Figure 4. These hinged deflector plates extend from front to rear of the heating chamber, and their hinges are located just above the top of the upper oven section when the latter is in its uppermost position. The free edges of the hinged deflector plates extend toward the longitudinal center of the heating chamber above the oven, and these plates may be swung on their hinges between the 100 dotted, horizontal position to the angular position in full lines as shown in Figure 4. On the front of the stove an operating indicator 42 is provided for moving the deflector plates and indicating their position 105 as best seen in Figure 3.

110 In Figure 6 it will be seen that while the hinged deflector plates extend the full length of the heating chamber, the spaced angle plates 37 which are attached at the underside of the top plate 6 of the stove, terminate a suitable distance from the front wall of the heating chamber to provide a transversely extending space 43 between the top plate of the oven and the top plate of the 115 stove which is occupied by the complementary ends of the deflector plates. Thus the deflector plates may be positioned to deflect the rising hot air currents over the top of the oven, and these currents then pass 120 toward the front of the stove to the transverse space 43 in which they are collected. The air currents then pass longitudinally toward the back of the stove, through the thimble and thence through the smoke pipe 125 130

40. When the top section of the oven is lowered the air currents passing over the top of the oven may enter the flue 38 by passing under the lower edges of the angle plates 5 as well as by passing to the collection space 43. In any event the hot air currents are caused to pass in close contact over the oven for the purpose of heating its walls and baking the articles contained therein. By 10 adjusting the upper oven section with relation to the lower section the conditions existing within the oven may skillfully and accurately be adapted for a variety of purposes, different foods, and various forms of 15 articles to be baked.

A convenient accessory for the stove is provided in the shelf 44 made up of metal and elevated above the top of the stove on legs 45, and an opening 46 is fashioned in 20 this shelf for the accommodation of the smoke pipe 40 as shown in Fig. 6.

When not desired for use it will be apparent that the structure may be dismantled by

first removing the upper and lower retaining frames, detaching the stove legs, then detaching the other removable parts as the top shelf, the fire pot, stove legs, etc., for packing in a small space.

Having thus fully described my invention, what I claim as new and desire to secure by Letters Patent is—

The combination in a furnace comprising end, side and top and bottom walls to form a heating chamber, an oven in said chamber and a grate below the oven, spaced plates attached at the under side of the top wall to form a flue located at the longitudinal center of said oven and thereabove and a smoke outlet to said flue, and oppositely disposed, hinged deflector plates at the sides of 35 said spaced plates and adapted to swing to adjusted position between the top of the oven and the top wall of the heating chamber.

In testimony whereof I affix my signature.
MATT'S JOHNSON.
